UNITED STATES PATENT OFFICE.

DENNIS DONAHOE, OF SIOUX FALLS, SOUTH DAKOTA.

ICE-WASHER.

No. 864,085.

Specification of Letters Patent.

Patented Aug. 20, 1907.

Application filed October 24, 1906. Serial No. 340,395.

To all whom it may concern:

Be it known that I, DENNIS DONAHOE, a citizen of the United States of America, residing at Sioux Falls, in the county of Minnehaha and State of South Dakota, have invented new and useful Improvements in Ice Washers, of which the following is a specification.

This invention relates to an ice washing attachment for ice delivery wagons, the object of the invention being to provide an attachment of this character which is arranged so as to not consume any of the ice-containing space and is designed to form a convenient means by which the pieces of ice may be cleansed before delivery to the customer.

A further object is to provide an attachment having a flexible discharge hose or nozzle and means for supporting the same in such a manner as to cut off the flow of water without the use of valves or equivalent devices.

The accompanying drawing shows a side elevation of an ice delivery wagon embodying my invention, a portion of the body of the wagon being broken away to show the storage tank.

In the drawing, 1 designates an ice delivery wagon of ordinary construction, which is provided at the forward end thereof with a seat box 2 in which is arranged a tank or reservoir 3 containing a supply of water.

Extending downwardly from the bottom of the tank is an outlet pipe 4 communicating with a delivery pipe 5. The pipe 5 is arranged below the body of the wagon and is suitably supported by the running gear and terminates at its rear end adjacent the hanger of the rear step 6.

To the rear end of the pipe 5 is connected one end of a flexible discharge nozzle or hose 7, the free end of which is adapted to be hung upon a hook 8 arranged upon one side of the wagon body at an elevation above the level of the water in the tank 2. Normally the nozzle is arranged as shown in the drawing with its free end sup-

ported by the hook 8, whereby, as the discharge end of the nozzle is arranged above the level of the water, the discharge of water therethrough is cut off. In order to wash a piece of ice which is to be delivered to a customer it is simply necessary to lift the nozzle out of engagement with the hook 8 and turn it down to the dotted line position, whereby the discharge end of the nozzle will be brought below the level of the water in the tank, and the water will flow therefrom and may be discharged upon the ice to remove sawdust and other refuse therefrom.

It will be seen that the device provides a convenient ice washing attachment for ice wagons which takes up none of the ice storage space and by which the operation of washing pieces of ice may be quickly and conveniently performed without loss of time, as the necessity of opening and closing valves to regulate the flow of water is entirely obviated. This is a desideratum in devices of this character in the delivery of ice in thickly settled districts where a large number of pieces are sold.

Having thus described the invention, what is claimed as new, is:—

An ice delivery wagon having a seat box, a water storage tank arranged within said box, a conducting pipe arranged below the body of the wagon and supported by the running gear, said pipe having an upwardly extending inlet projecting through the body of the wagon into the body of the tank and extending therefrom rearwardly to one side of the rear end of the body, a flexible hose or nozzle connected to the rear end of the pipe, and means upon one side of the rear end of the wagon body to support the free end of the hose or nozzle above the level of the water in the tank.

In testimony whereof, I affix my signature in presence of two witnesses.

DENNIS DONAHOE.
